AIRSCOOP FOR INTERNAL-COMBUSTION ENGINES

Frank C. Mock, South Bend, Ind., assignor to
Bendix Aviation Corporation, South Bend, Ind.,
a corporation of Delaware

Application November 23, 1942, Serial No. 466,619

44 Claims. (Cl. 123—122)

This invention relates generally to improvements in devices for supplying a moving column of air to the charge forming device of an internal combustion engine, and more particularly to devices of this class known generally as air scoops for supplying air to the charge forming device of an aircraft engine.

As is generally known, most charge forming devices utilize a venturi or other air metering element in the air supply passage for creating a suction or a differential pressure which varies in accordance with the air flow to the engine and which is used either directly or indirectly to determine the rate at which fuel is supplied to the engine.

Air scoops of the type known in the art have had inherent characteristics which variably disturb the relationship between the air flow and the suction created by the venturi and consequently interfere with the proper fuel to air proportioning. One such disadvantageous characteristic of known types of scoops has been their inability to maintain a uniform air velocity across the scoop, particularly at the entrance to the charge forming device. This non-uniform velocity of the various portions of the moving air column results in a suction at the venturi which is of a somewhat different amount from the suction which would prevail if the average velocity obtained at all points across the venturi. As a consequence, the fuel to air proportioning of the charge forming device is disturbed.

One of the reasons for this condition of non-uniform velocities has been due to the design of the scoop proper, as a result of which the air column, which generally is diverted by the scoop through an angle of about 90°, has a tendency to follow along the back or outer wall of the turn and cannot redistribute itself across the scoop in the limited available distance between the turn in the scoop and the entrance of the carburetor or charge forming device.

The problem of proper air scoop design to obtain accurate fuel metering has been complicated further by the necessity for heat valves or other arrangements for admitting protected or heated air to the air scoop at times when an aircraft is encountering atmospheric conditions which tend to form ice in the air scoop and/or within the induction passage leading to the engine with the attendant danger of so clogging with ice the scoop or induction passage that continued flight is impossible, or possibly damaging the supercharger impeller as a result of large pieces of dislodged ice.

The majority of scoops of the prior art make no provision whatever for supplying heated air to the scoop during such times as it is needed to prevent icing or to aid in warming up the engine; and the few scoops which have made such a provision have an inherent disadvantage, particularly in partial heat position, that during operation with the heat on, the column of air entering the charge forming device is not of a uniform temperature but varies between wide limits. As a consequence, ice may be effectively eliminated in some portions of the carburetor, but not in others. In order most effectively to prevent icing at all points in the scoop and carburetor it is of course desirable that the heated air be uniformly distributed across the entire carburetor passage. Furthermore, the variations in density resulting from this temperature variation disturb the suction to air flow relationship and adversely affect the accuracy of fuel metering. In addition, the non-uniform temperature makes it difficult if not impossible so to locate the temperature compensating element of the charge forming device that it is subjected at all times to the average air temperature regardless of variations both in the rate of air flow, accompanying changes in engine load and speed, and in the relative amounts of heated and cold air supplied, as determined by the degree of opening of the heat valve.

The scoops known to the prior art have generally been provided with some sort of gate or flap valve generally pivoted to and forming a portion of the forward wall of the scoop, and arranged to open inwardly into the scoop to any angular position to restrict the normal cold air passage and simultaneously open a port to admit from under the engine cowling air which has been heated by passing over the engine. With such an arrangement, however, the air entering the normal cold air opening of the air scoop is diverted by the gate or flap valve so that it follows a path near the back wall of the scoop and has a relatively great velocity and pressure both because of being confined to the outer portion of the bend and because of the ramming action from the forward velocity of the plane. On the other hand, the heated air is directed by the valve so that it tends to follow the forward wall of the scoop and has a relatively low velocity and pressure because of the resistance to air flow under the cowling and because of the absence of ramming action. Thus cold, high velocity, high pressure air tends to be concentrated along the outer or rear wall of the scoop and hot,

low velocity, low pressure air tends to be concentrated along the inner or forward wall of the scoop. This non-uniformity of the air column entering the charge forming device has made it difficult to maintain proper fuel metering.

In addition, since the cold air is at a greater pressure, due to ramming action, than the warm air, it is impossible to obtain a gradual application of heat by gradually opening the flap valve just referred to. Initial opening of the flap valve merely allows a portion of the high pressure cold air to escape through the warm air port, and does not result in the admission of any heated air. With such heat control the valve must be opened a substantial amount before the cold air supply is so restricted that warm air may enter through the warm air port, and the limited remaining travel of the valve changes the air supply from full cold to full hot. The heat valve is thus ineffective through the initial portion of its range of movement and too sensitive through the remaining portion.

With these and other problems in mind it is an object of this invention to provide an air scoop which will insure uniform velocity to the air stream moving through it.

Another object is to provide an air scoop which will provide a uniform velocity air column to the charge forming device.

Another object comprehends the inclusion of means located in the passages of an air scoop which will insure uniform velocity in the moving air column when it reaches the charge forming device.

Still another object is the provision of a restriction in the air scoop which will divide the moving column of air so that it will have the desirable velocity qualities when it reaches the charge forming device.

Yet another object is to provide a device for supplying air to a charge forming device which is readily adjustable to supply heated air to the charge forming device at a uniform velocity and pressure, as for example when an aircraft is encountering icing conditions.

Still another object is the provision of means at the control of the pilot or flight engineer whereby there will be given "feel" to the operator, so that the position of the control for admitting cold, protected, or heated air to the scoop and to the charge forming device will be known to the operator.

Another object comprehends a dual means of supplying a column of air to the charge forming device which has been heated either by (1) passing over the engine and protected by the cowling and known as warm protected air, or (2) passing between the exhaust manifold and a jacket surrounding the manifold and known as hot air.

Another object of the invention is the provision of a heat control arrangement in which the cold air inlet is fully closed during operation in the warm protected air position. This is of particular advantage in that rain or snow may be entirely excluded without the resultant loss of power accompanying the use of full heat.

Yet another object comprehends the supplying of air to the charge forming device which may be heated to some temperature between (1) and (2) above and may be supplied to the charge forming device at the control of the pilot or the flight engineer.

A still further object is the provision of means

for eliminating icing by fully shutting off the entrance of a cold stream of air and concurrently opening an entrance to provide heated air to a charge forming device.

Still another object of the invention is the provision of a means whereby heated air may be supplied even though an obstruction such as ice is on the edge of the cold air door and/or its seating surface.

A still further object is the provision of means for supplying heated air to a charge forming device, the temperature of the air being selectable as desired depending upon the conditions of flight.

Other features and desirable objects of this invention will be apparent from a study of the description and drawings forming this specification, in which:

Figures 1 and 2 are cross sectional views of a known type of air scoop connected to a charge forming device and showing various normally experienced velocity characteristics of the moving column of air as it enters the charge forming device;

Figure 3 is a view partially in section of a preferred embodiment of the air scoop made according to the present invention;

Figure 4 is a cross section taken substantially along the line 44 of Figure 3;

Figure 5 is a somewhat schematic cross section of an air scoop made according to the present invention in the full cold air position, the velocity characteristics of the column of air entering the charge forming device being shown vectorially;

Figure 6 shows in cross section an air scoop made according to the present invention and shown positioned with reference to an aircraft engine, with the heat valve for controlling the entrance of heated air shown in a position whereby warm protected air is admitted to the scoop;

Figure 7 is a cross section of the scoop, shown in the partial hot air position, the scoop being positioned with reference to an aircraft engine and cowling; and

Figure 8 is a cross section of the scoop shown in the full hot air position, its location with reference to an aircraft engine being shown schematically.

With reference to Figure 1 there is shown a scoop 20 of a type known to the prior art secured to an entrance conduit 22 of a charge forming device which may be of any desired type, the one shown at 24 being of the type disclosed in my pending application Serial No. 362,572, filed October 24, 1940. The charge forming device 24 may comprise a boost or primary venturi 26 and a main or secondary venturi 28 for determining the metering of fuel to a column of air which is supplied to an aircraft engine.

The path of the moving column of air is indicated generally by the light lines 30, the spacing of the lines being proportional to the velocity of the moving air column, i. e. lines which are closely spaced indicate points of higher velocity, and lines which are relatively widely spaced indicate points of lower velocity. The velocity vectors indicated at 32, and the vector diagram of the air stream entering the primary venturi 26 is shaped, for example, in the form of a composite rectangle and trapezoid. The vector diagram, sometimes referred to as the velocity pattern, is not at all stable for known types of scoops but will change with variations in the rate of air flow, the angle of attack of the plane or with other variations in flight conditions.

With reference to Figure 2 there is shown a scoop 120, of the same type shown in Figure 1, secured to the entrance conduit 122 of a charge forming device indicated generally at 124. A primary venturi 126 and a main or secondary venturi 128 are also indicated. The pattern of the moving column of air here illustrated as exemplifying another velocity pattern commonly experienced is somewhat different from that shown in Figure 1, that is, the velocity may vary uniformly from the front wall of the scoop 120 to the back wall. For example, the velocity vectors may be represented in the vector diagram 132, which is trapezoidal in shape, showing the lowest value of the velocity vector adjacent the forward wall of the scoop 120, and varying substantially uniformly to the highest value at the back wall of the scoop.

However, the velocity characteristics of the moving column of air in scoops known to the prior art may take different forms. Sometimes the characteristic has a recognizable regular pattern while at other times the velocity distribution is quite irregular and not in accordance with any known pattern. In general, however, relatively high velocities tend to prevail adjacent the back wall of the scoop and relatively low velocities adjacent the front wall.

The scoops which have been shown in Figures 1 and 2 may be of a type which is rectangular in shape at the forward opening adjacent the cowling of the aircraft engine, and which may vary in contour so as to fit top decks 23 and 123 of the charge forming devices 24 and 124 at a point anterior to the primary venturis 26 and 126. Although the scoops 20 and 120 generally have rectangular entrances they may have elliptical shaped entrances, for example, or circular, depending largely upon designer's choice. However, a preferred type has an entrance which is rectangular, preferably with the minimum dimension in the vertical plane, the body thereof being also rectangular and faired to meet the dimensions of the top deck of the charge forming device.

A preferred embodiment of the scoop made according to the present invention is shown in Figures 3 and 4. This embodiment has been found to be particularly satisfactory for the purposes intended, but it is to be understood that the invention is not to be limited to the embodiment shown, other arrangements falling within the spirit and scope of this invention to be permitted according to the claims appended to the end of this description.

The air scoop which is indicated generally by the ordinal 200 is adapted to be flexibly mounted on an adapter 201 which in turn is secured in any known manner to the top deck 202 of a charge forming device indicated generally by the ordinal 204. The flexible mounting for the scoop 200 may be an elastic boot 203 which is fastened to the scoop 200 and the adapter 201, as by clamping rings 205. This assembly will permit movement between the scoop 200 and the charge forming device 204, and is ordinarily necessary, since the scoop may be secured to a structure, as for example, an aircraft, and since the engine on which the charge forming device 204 is generally supported may be somewhat flexibly mounted with respect to the aircraft or supporting structure.

The charge forming device 204 may include a boost or primary venturi 206, a main or secondary venturi 208, and a plurality of impact tubes

210 located adjacent the secondary venturi 208, the pressure in the venturi 206 and the pressure transmitted through the tubes 210 being utilized to determine the proper metering of fuel.

5 The scoop 200 comprises an entrance passage 212 which receives a moving column of air, the velocity of which is given to it by the propeller wash, the movement of the aircraft through the air and the suction created by operation of an internal combustion engine. The entrance passage 212 extends in a generally horizontal direction until it intersects a riser 214 of the scoop 200 forming a throat 216. The throat 216 has a cross section as indicated and is formed by a curved outwardly bulged back wall 218 faired into an upper wall 220 of the entrance passage 212, and into a back wall 222 of the riser 214, and by a forward curved wall 224 which connects a lower wall 226 of the entrance passage 212 and a forward wall 228 of the riser 214. A rotary door or heat valve 225 forms a part of the forward curved wall 224 when the scoop 200 is in the full cold air position as shown in Figures 3 and 4. The door 225 is rotatable to positions other than that shown in Figures 3 and 4 to permit the entrance of protected or heated air to the scoop 200 and the charge forming device 204. The detailed description of the rotary door 225 and its operation will appear later in this specification.

10 30 Within the throat 216 is positioned an "island" generally of the shape indicated in Figure 3. While the shape shown has been found to be preferred for the purpose desired, it is shown for purposes of illustration only, other shapes and contours fulfilling the purpose being within the scope of this invention.

35 The "island" 230 is secured to the scoop 200 in any known manner as by cap bolts 232 passing through suitable holes in flanges 234 attached to the island 230 and threaded into the scoop 200. The island 230 has a relatively sharp leading edge 236 which preferably occupies a position vertically disposed from the horizontal plane which bisects the entrance 212 of the scoop 200 and preferably above said plane in the manner shown. Starting at the leading edge 236 the contour of the island 230 is such that its upper surface 238 and trailing surface 239 are spaced from the walls 220 and 218 and generally varying in distance from the walls 220 and 218 according to the desired function of the scoop 200. Again starting at the leading edge 236 the contour of the island 230 is such that a forward surface 242 varies in distance from the curved forward wall 224 according to a desired function later described in this specification. The island 230 may terminate, as shown, in a substantially transversely extending surface 244, which, if desired, may be somewhat rounded, to complete the outline of the island.

40 45 50 55 60 65 70 75 Between the upper wall 220 and the curved wall 218 is positioned a thickened portion 240 which is faired into upper wall 220 and curved wall 218 so that smooth flowing surfaces are presented to the moving air column. The thickest section at portion 240 of the upper wall 220 is opposite the uppermost point of the surface 238 whereby a minimum area passage indicated at 241 obtains for the moving air column. Since this restriction in area between surface 238 and the surface at 240 to the moving air column gives way to increasing areas between the curved wall 218 and the trailing surface 239, and since the surfaces presented are smooth and unbroken, the velocity of

the air flowing around the outside of the island is gradually decreased.

Between the forward surface 242 of the island 230 and the forward curved wall 224 of the scoop 200 are distances which vary substantially uniformly from a maximum at the leading edge 236 of the island 230 to a minimum at the intersection of forward surface 242 with surface 244 and near the point where curved wall 224 fairs into the forward wall 228 of the riser 214. The disposition of the island 230 with the curved wall 224 serves to constrict the area of the moving air column which has been divided at the sharp edge 236 of the scoop 230, thereby changing the velocity thereof. Assuming that no compression of the moving column of air takes place, the change in velocity of the air column will be inversely proportional to the ratio of the area between the leading edge 236 and the surface of the rotary gate 225 to the area between the upper portion of the forward wall 228 and surface 242 at the intersection thereof with surface 244. While it is not exactly accurate to assume that no compression of the moving column of air takes place when its cross section is diminished, yet for purpose of design it can be safely assumed.

For at times when it is desirable to prevent the entrance of air to the scoop 200 which may be ice-laden or otherwise unsuitable for ideal engine operation there is provided means at the control of the pilot or flight engineer for closing off the supply of such air to the engine and to open the charge forming device 204 to a supply of air which has been heated and protected by passing over the engine or, if warmer air is desired, through a jacket placed around the exhaust manifold.

Referring particularly to Figure 4 there is provided a butterfly valve 246 for preventing the entrance of cold air to the charge forming device 200 at such times when it is not wanted. Butterfly valve 246 is secured to a shaft 248 by any suitable method, preferably by cap screws 260 as shown. The butterfly 246 and its shaft 248 are so located that when the butterfly is in the full cold air position as shown in Figures 3 and 4 it is substantially in alignment with the leading edge 236 of the island 230, that is, a plane through the leading edge 236 will include the butterfly 246. The shaft 248 is journaled at each end in roller thrust bearings 252 and 253, which in turn are held respectively in cylindrical extensions 254 and 255 of the scoop 200. The shaft and bearing assembly is secured at its left end by a suitable bearing seal 256 and a castellated nut 258 which is locked in position by a cotter, not shown. The entire assembly just described is protected against the elements by a cap 260 which is pressed over the exterior surface of the cylindrical extension 254.

The right end of the shaft 248, which is journaled in bearing 253, has affixed thereto and abutting a shoulder in the shaft 248 a member 262 which includes a sealing ring 263 for bearing 253 and which is secured to the shaft 248 by a key 264. Member 262 has a cylindrical extension 266 around which is freely mounted a collar 268 integral with an arm 270 of a cam follower 272. The entire assembly is secured by a washer 274 and a castellated nut 276 threaded to the shaft 248 and held against turning by a cotter 278.

The arm 270 has a cupped portion 280 with a drilled passage 282 the axis of which is normal to the axis of the shaft 248 and spaced therefrom. An ear 284 projects from member 262 and extends in a direction parallel to the axis of the

shaft 248 to a position where it is spaced from the cupped portion 280. A bolt 286 passes through an opening in the ear 284 which is coaxial with the drilled passage 282 and through the drilled passage 282. A spring 288 is fitted over the shank of the bolt 286 and bears against a washer 290 at one end and against the cupped portion 280 of the arm 270 at the other end. Spring 288 is loaded by drawing up a castellated nut 292 threaded on the shank of bolt 286, which also bears against a washer 294. The nut 292 is locked in place by a cotter not shown.

The rotary gate 225 which has been described briefly with reference to the disposition of the island 230 in the throat 216 of the scoop 200 and the relation of the island 230 with reference to the walls of the scoop, comprises a portion of a cylinder, which portion is secured to radially extending arms 296 in the manner shown. Radial arms 296 have split ends 298 which are clamped rigidly to a shaft 300 by bolts 302. Shaft 300 is journaled at its left end in a suitable bearing 304 which in turn is held in an annular portion 306 of a circular plate 307 which is held to the scoop 200 by bolts 308 spaced equally near the periphery of the plate 307. The shaft 300 and bearing 304 is held at the left end by a flanged seal 308 for bearing 304 and a castellated nut 310 threaded on shaft 300 and secured thereto by a cotter not shown. The entire assembly is closed by a cap 312 which fits over the outer surface of the annular portion 306.

The right end of the shaft 300 is journaled in a bearing 314 held in a cylindrical extension 316 on the scoop 200. The bearing 314 is sealed by a ring 318 exterior to the bearing. Posed on the portion of the shaft 300 which extends beyond its journal in bearing 314 and the bearing seal 318 is a cam 320 which is essentially circular in shape and which has a guide 322 for the cam follower 272. Mounted exterior to the cam 320 is a pulley 324 which can be driven by a cable 326 from a control 328 in the cockpit over a suitable system of pulleys or the like which are not shown.

The cam 320 and the pulley 324 is secured to shaft 300 by a key 330. Cam 320 and pulley 324 are secured against axial movement on the shaft 300 by means of a washer 332 and a castellated nut 334 secured in turn by a cotter not shown.

The entire right-hand assembly described above is protected against the elements by a fairing 336 secured to the scoop 200 by any suitable means, which are not shown.

Cam 320 has a hub 321 which is integral with a web 323 and the guide 322. Secured to web 323 is a lug 325, shown in dotted outline in Figure 3, which engages a stop 327 which is integral with the cylindrical extension 316. When the lug 325 and stop 327 are in contact the scoop is in the full cold air position as shown in Figure 3. For limiting the rotation of the cam 320 and its attendant rotary door 225 in the clockwise direction a nose 329 of the cam 320 engages the other face of the stop 327.

Cam 320 has a contour as shown, and its guide 322 is composed of two circular portions 333 and 335, portion 333 being of a smaller mean radius than portion 335 and being smoothly joined thereto at one end by a reverse curved portion 338. Portion 333 is joined to a portion 331 which is parallel to a radius of the cam 320.

Scoop 200 has a pair of passages 340 and 342 which are in respective communication to warm protected air and to hot air. Passage 340 has an

area measured by a pair of webs 344 and 348, the spacing of the webs being the same as or slightly less than the chord length of the rotary door 225. Passage 342 likewise has an area measured by a web 348 and the web 346, the spacing of the webs being also the same as or slightly less than the chord length of the door 225.

The operation of the scoop which has been described with reference to Figures 3 and 4 is as follows.

The arrangement of parts shown in Figures 3 and 4 are those for normal flight conditions, that is, the air supplied to the charge forming device 204 does not need to be warmed to prevent icing, nor is the entering air column laden with ice. During such time the entering air column is passed at impact pressure through the scoop 200 in the manner shown in Figure 5, which shows in detail the change in the velocity characteristics of the air column as it passes around the island 230.

With particular reference to Figures 3 and 5, the entering column of air, which is divided by the island 230, is subjected to changes in velocity which has been described partly with reference to Figure 3 above. The air which passes above the butterfly 246 is first accelerated by the Venturi action between surfaces 240 and 238 and 239 and then decelerated thereafter since the cross sectional area between curved surface 218 and the trailing surface 239 becomes increasingly larger. This change in the velocity of the moving air column which courses in the upper half of the scoop 200 helps to equalize or average the velocity of the moving air column when it reaches the top deck 202 of the charge forming device 204.

Similarly, and again with particular reference to Figures 3 and 5, the air which enters the scoop 200 and is divided by the butterfly 246 is changed in velocity by the island 230. The position of the forward surface 242 of the island 230 with reference to the curved wall 224 and the gate 225 is such that a moving column of air between the surfaces of the elements just mentioned is gradually constricted in cross sectional area, thereby accelerating it.

This function of the scoop 200, to decelerate one part of the moving air column and accelerate the other part results in the velocity characteristics of the moving column of air where it enters the charge forming device 204 to be uniform in character. The representation of the uniform character of the moving air column as it enters the charge forming device is shown by the velocity vector diagram 350 of Figure 5, the vectors being shown of the same length to represent equal values.

For at times when the aircraft is encountering icing conditions the butterfly 246 of the scoop 200 is closed and air which has been warmed by passing over the engine or between an exhaust manifold jacket and the exhaust manifold is supplied to the charge forming device 204. The operation of the scoop under such conditions is as follows.

The pilot or the flight engineer will move the control handle 328 in a clockwise direction thereby imparting a similar movement to the pulley 324 through the cables 326. By the clockwise rotation of the pulley 324 a similar rotation is imparted to the shaft 300 and cam 320. This first movement serves to shut the butterfly 246 and move the rotary door 225 to the warm or protected air position, whereby passage between

webs 346 and 348 will be closed and the passage between webs 346 and 344 will be open.

The air and any entrained rain or snow entering through the main impact opening 212 is thus cut off and the carburetor is supplied with protected or non-impact air taken from under the engine cowling 352, as best shown in Figure 6. The protected air, so called since it is substantially free of any entrained rain or snow which is deflected or deposited out of the air supplied to the carburetor by virtue of the tortuous path through which the air flows, is warmed by passing between the engine and its cowling.

Simultaneous with the movement of the rotary door 225 to the warm protected air position is the closing of the butterfly valve 246. This is effected by the movement of arm 270 and its follower 272 in the guide 322 of the cam 320. This movement is transmitted to the member 262 through spring 288 and the ear 284 of member 262. The angular movement of cam 320 induces an angular movement in the arm 270, so that when follower 272 has moved first to the center of cam 320 and outward from the center to the intersection of portions 333 and 331 the butterfly 246 will be closed.

Should ice be present in the entrance passage 212 which would prevent the butterfly 246 from closing completely, it is still possible to move the rotary door 225 to the position whereby warmed air can be admitted. The overrunning connection provided by the spring 288 mounted on the bolt 286 permits a certain amount of angular travel of the arm 270 relative to the butterfly 246. Consequently, should the presence of ice prevent the full angular travel of the butterfly 246 to closed position, there still is the free angular travel of the arm 270 caused by the movement of the cam 320, thereby insuring against damage to the parts should ice be present in the entrance passage 212.

However, the angular travel of the butterfly 246 to the closed position is less than the angular travel required by the rotary door 225 to move from the cold air position of Figure 3 to the warm protected air position where the rotary door 225 will close the passage between webs 346 and 348. To permit this added angular travel, and not to change the position of the butterfly 246, which now would be in the closed position, the portion 333 of the cam 320 has a uniform radius. When the cam 320 has moved through such an angular distance the cam follower 272 will ride on the reverse curved portion 338. At such time the door 225 is in the warm protected air position, and the pilot or flight engineer is given "feel" through the cables 326 for telling him the rotary door 225 has reached such a position.

For adjusting the scoop to positions between the warm protected air position of Figure 6 and the full hot air position of Figure 8 the cam 320 may be rotated through a further angle as shown in Figure 7. Since the butterfly 246 is already in its closed position, further rotation of the cam 320 and the consequent engagement of the follower 272 with the cam portion 335 slightly rotates the lever 270 in a counterclockwise direction compressing the spring 288 and apprising the pilot that the door 225 has moved beyond its warm protected air position toward its hot air position.

When the cam 320 has moved to the limit of its clockwise angular travel, which travel is stopped by the engagement of nose 329 of cam 320 with stop 327 the scoop 200 will be in the full hot air

position of Figure 8, and the passage 340 between webs 344 and 346 will be closed by the rotary door 225.

Again with reference to Figures 6, 7 and 8 there is shown diagrammatically the position of the rotary door for the particular desired type of heated air supplied to the aircraft engine and charge forming device. In other than the full cold air position the rotary door 225 preferably should occupy either the warm protected air position or the full hot air position; however, if desired it may occupy the intermediate position shown in Figure 7. Figures 6, 7 and 8 also show the path of the heated air through the scoop 200. The suction created across the top deck of the charge forming device by the engine and supercharger draws the air around the island 230 in the manner shown. Since the butterfly 246 is closed at all positions other than the full cold air position, there is no possibility that the air entering the charge forming device 204 is composed of strata containing warmed air and cold air. As has been explained at the outset of this specification, such a condition results in inaccurate metering of fuel since the quality of the air supplied to the charge forming device is not uniform.

Thus has been described a novel and useful improvement in devices for supplying air to a charge forming device for an internal combustion engine. The embodiment of the invention described has been found to be a particularly suitable one for the purposes intended, but it is to be understood that the scope of the invention is in nowise limited to the embodiment shown, nor otherwise than by the claims appended hereto.

I claim:

1. A scoop for supplying a moving column of air to a charge forming device for an internal combustion engine comprising means for at times preventing the entrance of air at atmospheric conditions, means for controlling the entrance thereto of air from at least one of a plurality of heating sources, and means coupled with said second means for closing said first means to prevent entrance of air at atmospheric condition when said second means admits the air from said plurality of heating sources.

2. A scoop for supplying a moving column of air to a charge forming device comprising a passage open to air at atmospheric conditions, a riser connected to said charge forming device and intersecting said passage, means in said passage for at times preventing the entrance of air at atmospheric condition, a plurality of passages each connected to a source of heated air and having a common opening in the wall of said scoop, a door for said opening preventing the entrance of heated air to said scoop when said first passage is open to air at atmospheric condition, and means connecting said door and the first said means for closing the passage to air at atmospheric conditions when said door is opening to permit the entrance of heated air to said scoop.

3. A scoop for supplying a moving column of air to a charge forming device comprising a passage for admitting air at atmospheric conditions, a riser connected to said charge forming device and intersecting said passage, means in said passage for at times preventing the entrance of air at atmospheric conditions, a plurality of passages each connected to a source of heated air and having a common opening in the wall of said scoop, a rotary door in said passage for preventing the entrance of heated air to said scoop when said first

passage is open to air at atmospheric condition, and means comprising a cam connected to said door and a cam follower and arm connected to said first means for simultaneously closing the passage of air at atmospheric conditions when said door is opening to permit the entrance of heated air to said scoop.

4. A scoop for supplying a moving column of air to a charge forming device comprising a passage for admitting air at atmospheric conditions, a riser connected to said charge forming device and intersecting said passage, a normally open butterfly valve in said passage, a plurality of passages each connected to a source of heated air and having a common opening in the wall of said scoop, a rotary door in said passages, and means connecting said door and said butterfly for simultaneously closing the butterfly valve upon opening of the said door.

5. A scoop for supplying a moving column of air to a charge forming device comprising a passage for admitting air at atmospheric condition, a riser connected to said charge forming device and intersecting said passage, a butterfly in said passage for normally permitting the entrance of air at atmospheric conditions, a plurality of passages each connected to a source of heated air and having a common opening in the wall of said scoop, a door for said opening, and means comprising a cam connected to said door and a cam follower and arm connected to the butterfly for closing the butterfly when said door is moved toward open position.

6. A scoop for supplying a moving column of air to a charge forming device comprising a passage for supplying air at atmospheric condition, a riser connected to said charge forming device and intersecting said passage, means in said passage for normally permitting the supply of air at atmospheric condition, a passage connected to a source of heated air and having an opening in the wall of said scoop, a rotary door for said opening, and means comprising a cam connected to said rotary door and a cam follower and arm connected to said first means for closing the passage to air at atmospheric condition when said door is moved to open position.

7. A scoop for supplying a moving column of air to a charge forming device comprising a passage for supplying air at atmospheric condition, a riser connected to said charge forming device and intersecting said passage, a butterfly in said passage for normally permitting the supply of air at atmospheric condition, a passage connected to a source of heated air and having an opening in the wall of said scoop, a rotary door for said opening, and means connecting said door and said butterfly for closing the passage to air at atmospheric conditions when said door is moved to open position.

8. A scoop for supplying a moving column of air to a charge forming device comprising a passage for supplying air at atmospheric condition, a riser connected to said charge forming device and intersecting said passage, a butterfly in said passage, a passage connected to a source of heated air and having an opening in the wall of said scoop, a rotary door for said opening, and means comprising a cam connected to said door and a cam follower and arm connected to the butterfly for closing the passage to air at atmospheric condition when said door is moved to open position.

9. A scoop for supplying a moving column of air to a charge forming device for an internal combustion engine comprising an entrance passage

for air at atmospheric condition, means disposed in said passage for at times preventing the entrance of air at atmospheric condition, means controlling an entrance to said scoop for air from a plurality of heating sources, one of said sources supplying air which has been warmed by passing over the surfaces of said internal combustion engine, the other of said sources supplying air which has been heated by passing over the surface of an exhaust manifold of said internal combustion engine, and means coupled with said second means for closing said first means to prevent entrance of air at atmospheric conditions when said second means opens the entrance for air from said plurality of heating sources.

10. A scoop for supplying a moving column of air to a charge forming device for an internal combustion engine comprising an entrance passage, means disposed in said passage for at times preventing the entrance of air at atmospheric conditions, a door located at an entrance to said scoop of air from a plurality of heating sources, one of said sources supplying air which has been warmed by passing over the surfaces of said internal combustion engine, the other of said sources supplying air which has been heated by passing over the surface of an exhaust manifold of said internal combustion engine, and means coupled with said door for closing the first said means to prevent entrance of air at atmospheric condition when said door opens the entrance for air from said plurality of sources.

11. A scoop for supplying a moving column of air to a charge forming device for an internal combustion engine comprising an entrance passage for air at atmospheric condition, a butterfly valve disposed in said passage, means controlling an entrance to said scoop of air from a plurality of heating sources, one of said sources supplying air which has been warmed by passing over the surfaces of said internal combustion engine, the other of said sources supplying air which has been heated by passing over the surface of an exhaust manifold of said internal combustion engine, and means coupled with said second means for closing said butterfly to prevent entrance of air at atmospheric condition when said second means opens the entrance for air from said plurality of heating sources.

12. A scoop for supplying a moving column of air to a charge forming device for an internal combustion engine comprising an entrance passage for air at atmospheric condition a butterfly disposed in said passage, a door located at an entrance to said scoop of air from a plurality of heating sources, one of said sources supplying air which has been warmed by passing over the surfaces of said internal combustion engine, the other of said sources supplying air which has been heated by passing over the surface of an exhaust manifold of said internal combustion engine, and means coupled with said door for closing said butterfly to prevent entrance of air at atmospheric conditions when said door opens the entrance for air from said plurality of sources.

13. In a scoop for supplying air to a charge forming device for an internal combustion engine, means for normally permitting the entrance of air at atmospheric condition to said charge forming device, a door for at times permitting the entrance to said scoop of air from at least one of a plurality of heating sources, a cam connected to said door and operating the first said means through a cam follower and arm secured to said first means, said cam comprising a por-

tion for effecting movement of said first means to a position whereby air at atmospheric condition is prevented from entering said scoop when said door is moving to a position where air from one of the plurality of heating sources is admitted to said scoop, a portion on said cam for indicating when said door is moving to a position where air is supplied from more than one heating source, a stop for said cam whereby the door is positioned to admit air from another heating source, said movements of the cam subsequent to the movement closing the first said means leaving unchanged the position of the first said means.

14. In a scoop for supplying air to a charge forming device for an internal combustion engine, means for normally permitting the entrance of air at atmospheric conditions to said charge forming device, means for at times permitting the entrance to said scoop of air from at least one of a plurality of heating sources, a cam connected to said second means and operating the said first means through a cam follower and arm, said cam comprising a portion for effecting the movement of the first means to a position where air at atmospheric conditions is prevented from entering said scoop when said second means is moving to any position whereby air from the plurality of heating sources can be admitted to the scoop, a portion on said cam for indicating when said second means is moving to a position where air is supplied from more than one heating source, a stop for said cam whereby the said second means is positioned to admit air from another heating source, said movements of the cam subsequent to the movement closing the said first means leaving unchanged the position of the first said means.

15. In a scoop for supplying air to a charge forming device for an internal combustion engine, a butterfly for normally permitting the entrance of air at atmospheric condition to said charge forming device, means for at times permitting the entrance to said scoop of air from at least one of a plurality of heating sources, a cam connected to said means and operating the butterfly through a cam follower and arm, said cam comprising a portion for effecting the movement of the butterfly to a position whereby air at atmospheric condition is prevented from entering the scoop when said means is moving to any position where air from the plurality of heating sources can be admitted to the scoop, a position on said cam for indicating when said means is moving to a position where air is supplied from more than one heating source, a stop for said cam whereby the means is positioned to admit air from another heating source, said movements of the cam subsequent to the movement closing the butterfly leaving unchanged the position of the butterfly.

16. The invention as defined in claim 14 wherein in the arm is provided with a spring loading for indicating when said door is moving from one of said plurality of heating sources to the other.

17. In a scoop for supplying air to a charge forming device for an internal combustion engine, a butterfly for normally permitting the entrance of air at atmospheric conditions to said charge forming device, a door for at times permitting the entrance to said scoop of air from at least one of a plurality of heating sources a cam connected to said door and operating the butterfly, said cam comprising a portion for effecting the movement of the butterfly to a position whereby

air at atmospheric conditions is prevented from entering the scoop when said door is moving to any position where air from the plurality of heating sources can be admitted to the scoop, the movements of the cam subsequent to the movement closing the butterfly leaving unchanged the position of the butterfly.

18. In an aircraft, an internal combustion engine with a charge forming device therefor, a cowling for protecting said engine, an exhaust manifold for said engine, a jacket around said manifold for heating a supply of air, an air scoop having an entrance passage normally operative to supply a moving column of air to the charge forming device at substantially atmospheric temperature, means for at times permitting the entrance of air which has been warmed by passing over said engine and inside said cowling, said means also permitting at times the entrance of air which has been heated by passing over said manifold, and means coupled with said second means for closing said first means to prevent entrance of air at atmospheric condition when said second means permits the entrance of air which has been heated by the heating sources.

19. A fuel and air supplying device for an internal combustion engine comprising in combination: a charge forming device for said internal combustion engine, an air scoop connected to said charge forming device for supplying a moving column of air to the charge forming device including means for normally permitting the entrance of air at atmospheric condition, means for at times permitting the entrance thereto of air from one of a plurality of heating sources, and means coupled with said second means for closing said first means to prevent entrance of air at atmospheric conditions when said second means permits the entrance of air from said plurality of heating sources.

20. In combination with an internal combustion engine having a charge forming device therefor and an exhaust conduit, an air passage normally operative to supply air at atmospheric temperature to the charge forming device, a second air passage connected to the charge forming device in parallel with the first passage and passing in proximity to the heated portions of the engine to absorb heat therefrom, and a third passage connected to the charge forming device in parallel with the first and second passages and including a heating device associated with the exhaust conduit, valve means selectively operative to close either or both of said second and third passages, a second valve means in the first passage, and connecting means between the valve means operative to close the second valve means when the first valve means is moved to a position to open either of the second and third passages, and to open the second valve means when the first valve means is moved to a position to close both of the second and third passages.

21. In combination with an internal combustion engine having a charge forming device therefor and an exhaust conduit, an air passage normally operative to supply air at atmospheric temperature to the charge forming device, a second air passage connected to the charge forming device in parallel with the first passage and passing in proximity to the heated portions of the engine to absorb heat therefrom, and a third passage connected to the charge forming device in parallel with the first and second passages and including a heating device associated with the exhaust conduit, a rotary door selectively operative

to close either or both of said second and third passages, a second valve in the first passage, and connecting means between the valves operative to close the second valve when the first valve is moved to a position to close either of the second and third passages, and to open the second valve when the first valve is moved to a position to close both of the second and third passages.

22. In combination with an internal combustion engine having a charge forming device therefor and an exhaust conduit, an air passage normally operative to supply air at atmospheric temperature to the charge forming device, a second air passage connected to the charge forming device in parallel with the first passage and passing in proximity to the heated portions of the engine to absorb heat therefrom, and a third passage connected to the charge forming device in parallel with the first and second passages and including a heating device associated with the exhaust conduit, a valve selectively operative to close either or both of said second and third passages, a plate valve on the first passage, and connecting means between the valves including a spring loaded connection with the plate valve operative to close the plate valve when the first valve is moved to a position to open either of the second and third passages, and to open the plate valve when the first valve is moved to a position to close both of the second and third passages.

23. In combination with an internal combustion engine having a charge forming device therefor and an exhaust conduit, an air passage normally operative to supply air at atmospheric temperature to the charge forming device, a second air passage connected to the charge forming device in parallel with the first passage and passing in proximity to the heated portions of the engine to absorb heat therefrom, and a third passage connected to the charge forming device in parallel with the first and second passages and including a heating device associated with the exhaust conduit, a rotary door selectively operative to close either or both of said second and third passages, a butterfly in the first passage, and connecting means between the door and the butterfly operative to close the butterfly when the door is moved to a position to close either of the second and third passages, and to open the butterfly when the door is moved to a position to close both of the second and third passages.

24. In combination with an internal combustion engine having a charge forming device therefor and an exhaust conduit, an air passage normally operative to supply air at atmospheric temperature to the charge forming device, a second air passage connected to the charge forming device in parallel with the first passage and passing in proximity to the heated portions of the engine to absorb heat therefrom, and a third passage connected to the charge forming device in parallel with the first and second passages and including a heating device associated with the exhaust conduit, a valve selectively operative to close either or both of said second and third passages, a second valve in the first passage, and means comprising a cam connected to said valve and a cam follower and arm connected to said second valve operative to close the second valve when the first valve is moved to a position to close either of the second and third passages, and to open when said first valve is moved to a position to close both of the second and third passages.

25. In an elbow-shaped air scoop for an aircraft engine, a valve in the inlet of the scoop, an opening in the inner wall of the turn of said scoop posterior to said valve, a second valve controlling the opening in the inner wall, an island within the scoop positioned in the turn thereof and having its leading edge adjacent the said opening, said island approaching the inner wall of the scoop most closely at a point posterior to the opening, a source of heated air connected to the opening, and means for closing the first named valve when the second valve is opened.

26. The invention as defined in claim 25 wherein in the area for flow at the said closest point is smaller than the area of the said opening.

27. In an elbow-shaped air scoop for an aircraft engine, a valve in the inlet of the scoop, an opening in the inner wall of the turn of said scoop posterior to said valve, a second valve controlling the opening in the inner wall, a source of heated air connected to the opening, an island within the scoop positioned within the turn thereof for dividing the air which enters the scoop inlet or the opening in the inner wall, and means for closing the first named valve when the second valve is opened.

28. In an elbow-shaped air scoop for an aircraft engine, a valve in the inlet of the scoop, an opening in the inner wall of the turn of said scoop posterior to the valve, a second valve controlling the opening in the inner wall, a source of heated air connected to the opening, an island within the scoop positioned within the turn thereof for dividing the air which enters the scoop inlet or the opening within the inner wall, and means for closing the first named valve when the second valve is opened including a cam connected to the second valve and a cam follower connected to the first named valve.

29. The invention defined in claim 28 wherein the cam follower is provided with a spring override whereby the second valve may be opened with the first valve restrained in a partially open position.

30. The invention defined in claim 28 wherein the opening may be connected to air heated by one of a plurality of heating sources.

31. The invention defined in claim 28 wherein the opening may be connected to air heated by one of a plurality of heating sources, the cam follower is provided with a spring override, and the cam is provided with a contour to indicate when the second valve is moving to admit air from another of said heating sources to the scoop.

32. In combination with an internal combustion engine having a charge forming device therefor, an air passage normally operative to supply air at atmospheric temperature to the charge forming device, a second passage adapted to supply engine heated air to the charge forming device, a valve controlling the first passage, a second valve controlling the second passage, and means connecting said valves for closing the first valve and opening the second valve, said connecting means including a spring loaded override connection with the first valve whereby the second valve may be opened with the first valve restrained in a partially open position.

33. In an air scoop for a charge forming device of an internal combustion engine, a cold air inlet, a warm air inlet, and valve means operative simultaneously to close one of the inlets upon opening of the other inlet.

34. In an air scoop for an aircraft having a cowling, a cold air inlet receiving air exteriorly

of said cowling, a warm air inlet receiving air from under the cowling, a butterfly valve controlling the cold air inlet, a cylinder valve controlling the warm air inlet and a cam and follower connection between said valves for closing the butterfly valve when the cylinder valve is in open position.

35. In an elbow type air scoop having substantially right angularly related entrance and riser passages, an elbow-shaped island positioned in the turn of the elbow and bridges thereacross, said island having a relatively sharp leading edge in alignment with the entrance and a trailing end in alignment with said riser, the leading edge and trailing end being connected by separated walls which diverge from the leading edge to the turn of the elbow and thereafter converge to the trailing end, said walls being separated a maximum distance diagonally of the turn.

36. The invention defined in claim 35 wherein the trailing end of the island is more closely adjacent the inner wall of the riser than the outer wall.

37. In an elbow-shaped air scoop for an aircraft engine, a main air inlet adapted to open in the forward direction of the aircraft to be subjected to impact, an air inlet port in the wall of the scoop, an island within the scoop positioned within the turn thereof for dividing the air which enters the main scoop inlet or the inlet port, and valve means controlling the main inlet and inlet port and adapted to close the main inlet when the inlet port is open.

38. In an air scoop for a charge forming device of an internal combustion engine, an inlet for impact air, an inlet for protected air, an inlet for heated air, and valve means for closing the impact air inlet upon opening of either of the other inlets.

39. In an air scoop for an aircraft, an air inlet opening in the direction of travel of the aircraft to be directly subjected to impact, an inlet for protected air receiving air through a tortuous path, an inlet for heated air, and means for closing the first of said inlets upon opening of either of the other inlets.

40. In an air scoop for an aircraft engine, an air inlet subjected to direct impact of the air resulting from forward velocity of the aircraft, an inlet for protected air, an inlet for hot air, and valve means controlling said inlets.

41. In an elbow-shaped air scoop, for an aircraft, a main air inlet subject to impact, an opening in the inner wall of the scoop, a valve in the inlet, a valve in the opening, and a cam and follower connection between the two valves.

42. In an elbow-shaped air scoop for an engine having a main air inlet and a second air inlet in the wall of the air scoop, a valve in the main air inlet, a valve in the second air inlet, and a connection between the valves including a cam having two adjacent substantially arcuate portions of different radii and a substantially radial portion adjacent one of the arcuate portions.

43. In an elbow-shaped air scoop having angularly related inlet and outlet portions, an island immovably fixed in the turn of the scoop dividing the turn into inner and outer passages in parallel comprising a leading edge in alignment with the inlet portion, a trailing edge in alignment with the outlet portion, and inner and outer island surfaces interconnecting said edges and diverging from the leading edge to the turn of the scoop and thereafter converging toward the

trailing edge, said surfaces and the walls of the scoop being of such relative contour that the ratio of the inlet to outlet crosssectional areas of the inner passage is greater than the ratio of the inlet to outlet crosssectional areas of the outer passage.

44. In an elbow-shaped aircoop having angularly related air inlet and air outlet portions, an island immovably fixed in the turn of the scoop having a leading edge in alignment with the inlet portion and a trailing edge in align-

ment with the outlet portion whereby the turn of the scoop is divided into two passages in parallel, the outer wall of the turn of the scoop and the outer surface of the island being of such relative contour that the outer passage turns through an angle greater than that between the inlet and outlet portions and is of greater cross-sectional area adjacent the trailing edge of the island than adjacent the leading edge thereof.

FRANK C. MOCK.
